CLAIM

The ornamental design for a glove, as shown and described.

DESCRIPTION

FIG. 1 is a perspective view of our new design for glove.

FIG. 2 is a front elevation view of the glove of FIG. 1.

FIG. 3 is a first side elevation view (outer mitt side) of the apparatus of FIG. 1.

FIG. 4 is a second side elevation view (top of mitt side) of the apparatus of FIG. 1.

FIG. 5 is a third side elevation view (inner mitt side) of the apparatus of FIG. 1.

FIG. 6 is a fourth side elevation view (bottom of mitt side) of the apparatus of FIG. 1; and,

FIG. 7 is a rear elevation view of the multipurpose implement of FIG. 1; FIG. 7 shows surface shading.

In FIGS. 1–7, the broken lines are included for the purpose of illustrating environment and form no part of the claimed design. The broken lines for the trademark “KG” are included for the purpose of illustrating environment and form no part of the claimed design. The broken line showing of the flap portion and of the stitching is for the purpose of illustrating portions of the multipurpose implement and forms no part of the claimed design.
